DRAGLINE BUCKET

Harry A. Whitcomb and John W. Patch,
Welch, Okla.

Application January 9, 1943, Serial No. 471,868

1 Claim. (Cl. 37—135)

This invention relates to the art of earth moving and the like and more particularly to dragline buckets such as are attached to flexible cables, suspended from swingable booms, the latter being mounted on revoluble platforms carried by land vehicles having endless chain treads.

It is an object of the invention to provide a bucket of large capacity which holds approximately forty cubic feet of material when fully loaded, the parts of which are so constructed and arranged that the bucket will pick up, handle and move elongated objects weighing several tons.

Another object of the invention is to provide an open sided drag-line bucket construction wherein the component parts thereof are so shaped and welded together that the forward edge of the pick-up or bottom thereof is strongly reinforced for sustaining a comparatively great weight of solid rock or the like overhanging and extending far beyond the sides of the bucket.

More particularly a further object of the invention is to provide an open sided bucket formed of bars which are of oblong contour in cross section, the elongation of said cross section being disposed vertical in use and sustained spaced apart by braces welded thereto whereby the bars are so disposed that the comparatively great weight of an elongated rock or the like may be supported on the bottom of the open sided bucket without the employment of extraneous means, the upper portions of said bars being disposed convergently toward the medial and towing end thereof for distributing the stress incident to use without distortion.

Other and further objects and advantages of the invention will be understood from the following detailed description thereof, reference being had to the accompanying drawings in which:

Figure 1 is a side elevation of the new bucket attached to a portion of its towing chain, elevating, lowering and adjusting rigging, certain portions of said rigging being broken away and others being represented by dotted lines.

Figure 2 is a top plan view of the new device, the operating means therefor being omitted.

Figure 3 is a front elevation of a portion of the rigging shown in Figure 1 and a front elevation of the new bucket.

Figure 4 is a rear elevation of the bucket.

Referring now to the drawings for a more particular description, 10 indicates generally the new bucket, which includes a plurality of bars certain thereof being of different lengths. The bars are oblong in cross section, being approximately five times as wide as they are thick in cross sec-

tion. The medial and longest bar 12 is substantially J-shaped in side elevation and provided with a double clevis at its forward end for purposes later described. At each side of the medial bar 12 two substantially U-shaped bars 14 and 16 are disposed. As best shown in Figure 2 the bars 14 are longer in plan than the bars 16.

As best shown in Figure 1 the J and U bars are provided with pointed ends 18 which taper toward the lower side of the bucket and toward the ground during use.

The bars are maintained spaced apart and rigidly held together by means of three transversely disposed brace-bars 20, 22 and 24 which are respectively disposed at the bottom, rear and top of the bucket. The braces are of square material in cross section and three sides of each thereof are embedded into the J and U bars where the braces cross the bars, as shown in Figures 1 and 2.

The braces are welded rigidly to the bars at their junction for maintaining the pointed ends 18 disposed side by side in spaced apart parallelism at the bottom of the bucket.

As best shown in Figure 1, the inside of the bucket is lined with a heavy sheet of material 26 which extends across the back and bottom thereof, having a portion 26' extending forwardly, at the top of the bucket, for approximately one-fourth of the length of the bucket for preventing an overflow of material through the top of the bucket between the bars thereof during use.

The bottom portion 26'' of the sheet 26 extends forwardly of the bottom of the bucket to a point rearwardly of the pointed ends 18 of the bars, having tongue portions 28 which are arcuate and disposed downwardly between the bars.

The portions of the sheet 26 which abut the bars are welded to the latter for further bracing the bucket and particularly the bottom thereof. The U-bars are disposed parallel with respect to each other and with respect to the medial J-bar 12 to a point forwardly of the forward edge 30 of the sheet 26 where the oppositely disposed U-bars at the outer sides of the bucket are provided with portions 14', said portions being disposed convergently towards each other, having terminal ends 32 which are welded to the medial bar 12 rearwardly of the forward end of the bar 12, as shown in Figure 2.

Similarly the shorter U-bars 16 are provided with ends 34 disposed approximately midway between the ends 32 of the bars 14 and the upper cross brace 22, said ends 34 being rigidly welded to the medial bar 12 so that the longitudinal

length of the latter is prevented from bending transversely during use.

Prior to a welding of the brace bar 24 into place, rings 36 are welded to the bar 24, one each closely adjacent to the ends of said bar, as shown in Figure 4, for the reception there-through of ends of later described chains 40 and 42, and it will be understood that any suitable means may be employed for attaching the ends of the chains 40 and 42 to the rings 36.

The chains 40 and 42 are disposed so that the opposite ends thereof converge towards each other, being secured to a pin 44 of a pulley housing 46, as best shown in Figures 1 and 3.

As best shown in Figures 1 and 2, the forward end of the medial bar 12 is provided with a double clevis which includes a clevis 48 to which a heavy drag-line chain 50 is attached. A pin, bolt or other suitable keeper 52 is employed for pivotally attaching the clevis 48 to the bar 12, said pin also serving as a pivotal attachment for the clevis 54, the arms of the latter being disposed at the outer sides of the arms of the clevis 48.

A flexible cable 56 is employed, having an end 58 spliced or otherwise suitably secured to the clevis 54.

The cable 56 is rove over a pulley wheel 60 and between the guide walls of the pulley wheel housing 46, the other end of the cable being secured to a winding drum operated by a steam winch mechanism carried on a revolvable platform (not shown) in a well known manner.

The pulley housing 46 is provided with a pin, bolt or suitable keeper 62 to which an end of a second flexible cable 64 is attached. The cable 64 extends over a pulley 66 secured to an outer end of a swingable boom 70, as shown in Figure 1. The other end of the boom is pivotally secured to the above mentioned platform.

At times when the cable 56 is taut, the bucket is provided with a three point suspension by means thereof in conjunction with the chains 40 and 42. At times when the boom and cable are employed for moving the bucket above the ground, the cable 56 may be utilized for tilting the pointed ends 13 of the bars toward or away from the ground, in a well known manner, for scooping material into the bucket at times when the chain 50 is employed for drawing the bucket towards the winch to which the chain 50 is attached.

As thus described, it will be understood that the new bucket is adapted for numerous utilitarian purposes, including operations which involve shale, slate, rocks, frozen earth, and particularly elongated heavy objects which are not adapted to be moved by a conventional drag-line bucket having walls at the sides thereof. It has been found in actual practice that the bucket of the present invention is well adapted for use in tearing loose and moving several types of slate and rock without blasting, and in in-

stances where the latter are provided with seams formed by nature whereby an appreciable saving of labor is consummated, together with powder and the like.

- 5 The new bucket is intended for use and is of particular advantage for excavating purposes in country having outcroppings of rock formation, and it is well known that a large, heavy, and elongated slab of stone which it is desired to 10 move heretofore has required a separate blasting operation to fractionate the same to sizes suitable for moving, and the new device aims to provide means for handling said large slabs without fractionating the same, and to also provide 15 means for obviating certain of the undesirable features of the prior art practice.

In the drawings 66 indicates a large elongated slab of rock weighing several tons, and in operation the boom 70 is swung so that it is disposed medially at right angles to the length of said 20 rock, the pointed ends 13 of the pick-up base being suitably tilted, whereupon the chain 50 and bucket are caused to be moved toward the winch, causing the slab 66 to be disposed on the portion 26" of the sheet 26 with the ends of said slab projecting outwardly beyond each side of the 25 open sided bucket of the present invention, the cable 64 shortened for raising the weight and the boom swung for moving the slab to a desired 30 location. At this time the cable 56 is released for dumping the slab.

From the foregoing description it is thought to be obvious that a drag-line bucket constructed in accordance with our invention is particularly 35 well adapted for use by reason of the convenience and facility with which it may be assembled and operated, and it will also be obvious that our invention is susceptible of some change and modification without departing from the principles and spirit thereof and for this reason we 40 do not wish it to be understood as limiting ourselves to the precise arrangement and formation of the several parts herein shown in carrying out our invention in practice except as claimed.

45 We claim:

In a drag-line bucket, a substantially J-shaped bar, a plurality of substantially U-shaped bars disposed at both sides of said J-shaped bar, said bars having pointed ends disposed in side by side 50 spaced apart parallelism at the bottom of the bucket, a plurality of transversely disposed braces secured to the J and U bars for maintaining said parallelism, sheathing secured to the inner sides of said J and U bars at the back and bottom thereof for providing an open sided bucket, and means for attaching a drag chain at the other end of said J bar, the other ends of said U bars being disposed inclinedly toward and secured to the sides of said J bar for distributing 55 stress during operation.

HARRY A. WHITCOMB.
JOHN W. PATCH.
